CLAIM

The ornamental design for a display screen or portion thereof with graphical user interface, as shown and described.

DESCRIPTION

The FIGURE is a front view of a display screen or portion thereof with graphical user interface showing our new design.

The dashed broken lines in the FIGURE show a display screen or portion thereof, and form no part of the claimed design.

The dot-dash broken line in the FIGURE and the areas between the dot-dash line and the dashed broken lines show portions of the graphical user interface that form no part of the claimed design.

1 Claim, 1 Drawing Sheet
